Specification for Design.

Patented Sept. 22, 1914.

Application filed June 20, 1914. Serial No. 846,396. Term of patent 7 years.

To all whom it may concern:

Be it known that I, ROBERT JAMES MARSHALL, citizen of the United States, residing at East Liverpool, in the county of Columbiana and State of Ohio, have invented a new, original, and ornamental Design for Vehicle-Tires, of which the following is a specification.

Reference is had to the accompanying drawing, in which:—

Figure 1 is a plan view of a portion of a vehicle tire showing my ornamental design.

Fig. 2 is a transverse sectional view of the same.

I claim:—

The ornamental design for a vehicle tire, substantially as shown.

In testimony, that I claim the foregoing as my own, I have hereto affixed my signature in the presence of two witnesses.

ROBERT JAMES MARSHALL.
